[**] Term: 14 Years

[57] CLAIM

[21] Appl. No.: 54,450

The ornamental design for a sheath for a concrete finishing
float tool, as shown and described.

[22] Filed: May 14, 1996

DESCRIPTION

[51] LOC (6) Cl. 03-01

FIG. 1 is a front perspective view of the sheath for a
concrete-finishing, float tool of my invention;

[52] U.S. Cl. D3/228

FIG. 2 is a top plan view thereof;

[58] Field of Search D3/228, 215; 224/234,
224/240, 660, 666, 904

FIG. 3 is a front elevational view thereof;
